UNITED STATES PATENT OFFICE.

LOUIS S. MATTOX, OF PLAINFIELD, NEW JERSEY.

TRAIN-CONTROLLER.

1,060,473.

Specification of Letters Patent. Patented Apr. 29, 1913.

Application filed March 15, 1910. Serial No. 549,433.

To all whom it may concern:

Be it known that I, Louis S. MATTOX, a citizen of the United States, residing at Plainfield, in the county of Union and State of New Jersey, have invented new and useful Improvements in Train-Controllers, of which the following is a specification.

This invention relates to devices for automatically stopping trains and its object is 10 to provide tripping means applied to the track and put in action by an attendant or other qualified party to operate certain mechanism on a locomotive whereby the steam supply is shut off and the brake is 15 applied, as will be more fully described in the following specification, set forth in the claims and illustrated in the drawings, where:

Figure 1 is a side elevation of the rear 20 end of a locomotive showing the device for operating the throttle and brake applied thereto. Fig. 2 is a side view of the trip. Fig. 3 is an end elevation. Fig. 4 is a perspective view of the track showing the means 25 for operating the trip. Fig. 5 is a plan view of same. Fig. 6 is a detail view partly in section. Fig. 7 is a modified view of the trip operator.

The device is adapted to be located within 30 in the rails of a track and preferably adjacent to one of the rails and is supplied with compressed air or other similar means contained in a tank 10 and adapted to pass through a pipe 11 to supply one or more 35 cylinders 12 in which a piston works and is adapted to be forced backward carrying with it the piston 13 and connecting rod 14, the latter being pivoted to a lever 15 inclosed within a box 16 secured to the ties. 40 The box 16 has a cover 17 pivoted to the box at 18 and is adapted to occupy a horizontal position or to be thrown up and inclined as shown in the drawings. The forward part of the box 16 has an opening 18 through which the rod 14 operates and when 45 the air pressure is removed the weight of the top will carry the lever 15 downward and pull the piston forward.

At one side of the locomotive is secured 50 a frame 20 having pivoted at its lower end a lever 21 whose lower end is adapted to come in contact with the inclined face of the box top 17 and be swung backward. Normally the top end of this lever 21 supports a plunger 22 adapted to slide in the 55 frame 20 and force downward by a spring

23 surrounding the plunger and confined between the partition 24 and the shoulder 25. The upper end of the plunger carries a bar 26 having vertical pins 27 which play 60 through a partition 28 and are adapted to receive the perforated plates or hooks 29 carried by the ends of cords 30 and 31. As will be seen in Fig. 1, the cord 31 is arranged to connect with the end of a cock 32 65 which controls the flow of steam from the boiler to the cylinders and which is provided with a spring 33 to close same. When the lever 21 strikes the box top and is thrown toward a horizontal position, the plunger 22 70 is released and descends carrying the pins 27 through the perforations in the partition 29 and allowing the cord 31 to fly loose and the valve 32 is then closed by means of a spring 33, thus shutting off the steam supply 75 to the cylinders. The cord 30 controls a valve 34 in the air brake supply pipe 35 and when the hook 29 at the end of cord 30 is released this valve is opened automatically and the air supply is furnished to the 80 brake cylinder 36 and the brake supply. It will thus be seen that this operation of shutting off the steam and applying the brake is practically simultaneous and it is done automatically and needs the assistance of none 85 of the train hands when the inclined top is in its operative position.

In Fig. 7 is shown a box with the usual top which is adapted to be thrown by means of a rod or cord 38 which may be attached 90 to a switch lever or other device which is used in connection with railroads and adapted to be operated on certain occasions. When used in connection with a switch throwing lever, the rod 38 may be operated 95 when the switch is thrown to elevate the box top 17 and stop or decrease the speed of a train traveling in that direction.

It is obvious that the parts may be otherwise arranged and modified without departing from the essential features above described.

What I claim as new and desire to secure by Letters Patent is:

1. In a locomotive controller, the combination of a self closing throttle valve, a self closing air brake valve, a vertical spring pressed plunger having pins at its upper end, an element connected at one end to the self closing throttle valve and having its opposite end detachably connected to one of the pins, a second element connected at one

end to the self closing air brake valve and having its opposite end detachably connected to another of said pins, a trip below the plunger arranged for holding the plunger in an elevated position against the action of its spring, and an obstruction on the road bed adapted to be arranged to strike the trip and permit the plunger to descend under the action of its spring and thereby cause the pins of the plunger to disconnect from said first and second named elements.

2. In a train controller, the combination with a self closing throttle valve, of an air brake valve adapted to close automatically, a frame carried by the locomotive, a plunger having pins at its upper end, a cord for connecting one of the pins with the air brake

valve to hold it open and having at one end a ring fitting over the pin, a second cord connecting the other pin with the throttle valve 20 to hold it open and having at one end a ring fitting over the said other pin, a spring forcing the plunger downward, a trip beneath the plunger to hold it in its elevated position, and an obstruction on the track 25 adapted to throw the trip to release the plunger and the rings from the pins.

In testimony whereof I affix my signature in presence of two witnesses.

LOUIS S. MATTOX.
